AUTOMOBILE MODULE FOR MOUNTING COMMUNICATION EQUIPMENT

Dow L. Hestand, 1401 W. Sunset Blvd.,
Odessa, Tex. 79763

Filed May 2, 1973, Ser. No. 356,640

Term of patent 14 years

Int. Cl. D12—16
U.S. Cl. D12—155

FIG. 1

FIG. 2

FIG. 3

FIG. 1 is a right front perspective view of an automobile module for mounting communication equipment showing my new design;

FIG. 2 is a left rear perspective view thereof; and

FIG. 3 is a left front perspective view thereof, it being understood that the dotted lines are for illustrative purposes only.

I claim:

The ornamental design for an automobile module for mounting communication equipment, substantially as shown and described.
